United States Patent Office.

ELIJAH W. MERRILL, OF WEST BUXTON, MAINE.

Letters Patent No. 75,640, dated March 17, 1868.

IMPROVEMENT IN HARVESTERS.

The Schedule referred to in these Letters Patent and making part of the same.

TO ALL WHOM IT MAY CONCERN:

Be it known that I, ELIJAH W. MERRILL, of West Buxton, in the county of York, and State of Maine, have invented a new and useful Improved Mower; and I hereby declare the following to be a full, clear, and exact description thereof, which will enable others to make and use my invention, reference being had to the accompanying drawings, forming part of this specification, in which is shown a plan of my invention.

My invention aims at providing a simple method of attaching the vibrating-arm to the cutters, and procuring an easy and effectual way of throwing said arm out of gear when necessary.

I effect the attachment by providing the rod connected with the cutters with a head, *a*, capable of moving in a longitudinal slot, *b*, in the frame of the machine. This head is provided with a circular aperture, into which passes the rod *c* attached to the vibrating-bar. This rod is movable therein in the direction of its length, in order to allow it to slip easily backward and forward when the arm *d* is thrown into or out of gear. By means of this rod the vibrating motion of the rod *d* is directly transmitted to the cutters, without the loss of power by friction, which necessarily attends the use of gearing, &c.

The arrangement for disengaging the arm from its connection with the machinery giving motion to the same is as follows: The vibrating-arm *d* is pivoted upon a swinging lever, *x*, fastened at one end by a pivot to the frame of the machine. The other end of this swinging lever *x* is provided with a hand-bar, *f*, by which it may easily be moved backward or forward, carrying with it the arm *d*, and engaging or disengaging it, as the case may be. This is secured in either position by a catch-pawl, *y*, which is so attached to the frame as to allow its ends a vertical motion. At the extremity *i* of this pawl is a lip, which shuts over the end of the lever *x*, holding it firmly in place. When the arm *d* is to be thrown out of gear, by pressing the foot upon the end *k* of the catch-pawl, the end *i* is raised, relieving the swinging lever *x* from the lip, when it may be easily moved by the hand-lever *f*. When it is thrown out of gear the pawl *y* is returned to its place by a spring under the extremity *k* of the same, and effectually prevents, by means of its lip, the lever *x* from slipping into gear by any action of its machinery, thus adding much to the safety of the machine. The motion is communicated to my machine by a spirally-curved cam, *g*, which receives its motion from a small gear-wheel, moving on a larger reverse gear attached to the inner side of the wheel of the mower.

I do not claim this cam, nor the method of giving it its motion; neither do I claim the reciprocal motion of the bar *d* and the cutters, when produced in the manner described, for I am aware that these are not new; but my invention relates to a simple and effective method of connecting, holding in connection, and disconnecting the operating parts, as herein described; but

What I do claim as my invention, and desire to secure by Letters Patent, is—

The vibrating-arm *d*, in combination with and when set upon the swinging lever *x*, together with the hand-lever *f* and catch-pawl *y*, the head *a* and rod *c*, when arranged as and for the purpose specified.
